UNITED STATES PATENT OFFICE.

CARL G. GUSTAFSON, OF SIOUX CITY, IOWA.

ANGLE-COCK.

1,130,399.

Specification of Letters Patent. Patented Mar. 2, 1915.

Application filed August 16, 1912. Serial No. 715,444.

To all whom it may concern:

Be it known that I, CARL G. GUSTAFSON, citizen of the United States, residing at Sioux City, in the county of Woodbury and 5 State of Iowa, have invented certain new and useful Improvements in Angle-Cocks, of which the following is a specification.

This invention relates to angle cocks for train-pipes, and has for its object the provision of an angle cock which may be operated from either side of the car and which will be so constructed as to avoid the liability of freezing.

The invention will be hereinafter fully 15 described and its novel features subsequently pointed out in the claim following the description.

In the accompanying drawings which 20 fully illustrate the invention: Figure 1 is a rear elevation of the angle cock, the operating handle being removed; Fig. 2 is a front elevation of the same, the plug and cap for closing the plug chamber being removed; Fig. 3 is a side elevation of the 25 angle cock; Fig. 4 is a vertical transverse section; Fig. 5 is a vertical longitudinal section of the angle cock showing all the parts assembled; Fig. 6 is a rear elevation with the handle in position; Fig. 7 is a detail view of the latch mounted in the handle; Fig. 8 is a detail end view of the handle.

My improved angle cock, 3, is secured directly on the end of the train-pipe by a 35 threaded connection, as indicated at 4, and a hose 5 is connected to the end of the angle cock opposite the train-pipe to extend to the train-pipe coupling, as will be readily understood.

The angle cock consists of a body having 40 an upper arm 6 which is threaded onto the end of the train-pipe, the main body of the cock depending from the said upper arm 6 and the lower extremity of the body being 45 turned at a slight angle to form the annulus 7 to which the hose coupling 8 is fitted. The angle cock is bored throughout its length to provide a passage for the fluid and in the down-turned portion the said bore or passage 50 is enlarged laterally to form a tapered seat for a bushing 9 which is provided with diametrically opposite ports 10 and is adapted to be forced in through the larger end of the tapered seat with sufficient pressure to 55 wedge it firmly in place. The plug, 11, has a conical body adapted to seat within the

said bushing and turn therein and has one end extended, as indicated at 12, to project through the side of the body of the cock and have a handle secured thereto. A central 60 diametrical passage or port 13 is formed through the plug so that, if the plug be turned to a position in which the port will register with the openings 10 in the bushing, the flow through the cock will be uninterrupted and the air or steam may pass therethrough to the coupling, while, if the plug be turned to a position in which the port 13 will extend across the plane of the openings 10 at a right angle thereto, the 70 flow will be cut off and the train-pipes may be uncoupled without any appreciable loss of steam or air. On the side of the body, immediately adjacent the larger end of the bushing seat, is formed an external collar 75 14 which is internally threaded to be engaged by the cap 15 constituting a closure for the plug chamber. The cap 15 is chambered on its inner side, as shown at 16, and is provided externally with an annular 80 flange or rib 17 which, by engaging against the outer surface of the angle cock, limits the inward movement of the cap and thereby prevents injury to the threads. The larger end of the plug is formed with a 85 socket or recess 18 and a spring 19, having its opposite ends seated in said socket and the chamber of the cap 15, serves by its expansion to hold the plug firmly and evenly 90 to its seat so that an air-tight joint between the plug and the bushing will be effected, while, at the same time, the plug may be readily turned when it is necessary to cut off or set up the flow of fluid through the cock. An opening 20 extends through the 95 end of the plug between the port 13 and the socket 18, so that the fluid may pass into the chamber of the cap 15 and thereby aid the spring 19 in holding the plug to its seat, while a drain passage 21 is provided at the 100 wider end of the plug to permit water of condensation to pass from the chamber 16 into the bore of the cock below the plug and thereby escape so that all liability of the 105 said water freezing and causing the plug to stick will be overcome.

The projecting end 12 of the plug is angular, as shown most clearly in Fig. 6, and is also constructed with a rib 22, so that an angular engagement between the plug and the handle 23 will be effected when the upper end of the handle, which is provided

with a similarly shaped transverse opening, is engaged over the end of the plug. The upper end of the handle and the projecting end of the plug are provided with openings 5 adapted to register, and a pin 24 is inserted through the said openings so as to lock the handle to the plug whereby movement of the handle, independently of the plug in any direction, will be prevented.

10 The upper end of the handle plays against a quadrant 25 formed on the adjacent side of the angle cock body, and this quadrant is provided at its opposite sides with the lugs 26 which constitute stops to limit the movement of the handle and is also provided with the diverging grooves 27 disposed at a right angle to each other and adapted to be engaged by a latch 28 carried by the handle so that the handle will 15 be held in either of its set positions. When the latch engages one recess or groove, the air will be cut out and when the latch engages the other groove or recess, the air will be cut in, as will be readily understood.

20 The latch 28 is seated within a tubular portion 29 of the handle, which tubular portion extends outwardly from the upper end of the handle at a right angle thereto and has the main body or lever of the handle 25 depending from its outer end. The outer end of the tubular portion or barrel 29 is internally threaded to receive a cap 30 which has an outer angular end adapted to be engaged by a wrench or similar tool when 30 inserting or removing the cap and is also constructed with a rib or flange 31 which limits the inward movement of the cap by engaging the outer surface of the handle, as will be readily understood on reference 35 to Fig. 5. The latch 28 is mounted in the barrel 29 in advance of the cap 30 and comprises a stem 32, an annular disk or body 33 at one end of said stem, and a locking tongue 34 projecting from the said disk or body toward the open end of the barrel. The end of the locking tongue 34 is tapered, as clearly shown in Fig. 7, to properly engage the inwardly converging walls of the grooves 27 and thereby avoid sticking in 40 the grooves, while, at the same time, the handle will be effectually held in either of its adjusted positions. The tongue 34 is flat, as clearly shown, and plays between the lugs or projections 35 formed within 45 the barrel at the end thereof so that rotary movement of the latch cannot occur and it will be constantly maintained in proper position to enter either groove 27. The annular body or disk 33 constitutes a stop to 50 prevent ejection of the latch by engaging the inner sides of the lugs 35, and a spring 36 is coiled around the stem 32 between the 55

60

said body or disk 33 and the cap 30, as clearly shown in Fig. 5, said spring tending by its expansion to project the latch so 65 that it will automatically engage either groove. When sufficient force is applied to the lever portion of the handle to turn the same and the plug, the tapered end of the latch, co-acting with the converging faces 70 or walls of the grooves, will permit the latch to automatically recede from the groove and compress the spring 36, but unless sufficient force is applied to the handle to turn the same laterally, the latch will hold the handle in its set position and consequently accidental turning of the plug will be prevented.

The depending lever portion of the handle is provided at its lower end with two 80 openings 37 which receive pivot pins whereby the inner ends of operating rods are attached to the handle. These rods extend laterally to opposite sides of the car and pass through suitable hangers. By actuating 85 the operating rods, the valve may be easily shifted and the latch will hold it in its shifted positions.

The operation and advantages of my improved angle cock are believed to be evident 90 from the foregoing description, taken in connection with the accompanying drawings, and detail mention of the same is deemed unnecessary.

By the use of my improvements, the necessity of the trainmen passing between the cars in order to operate the angle cocks is overcome so that life and limb will not be endangered and the cock may be easily operated from either side of the car and will 100 not be apt to freeze and stick in extreme weather.

What I claim is:—

An angle cock for train-pipes comprising a tubular body having a vertically disposed 105 portion, a tapered turning plug seated horizontally in said vertically disposed portion, means on the smaller end of said plug for turning the same, a socketed cap secured in the side of the body over the larger end of 110 the plug, an opening through said end of the plug establishing communication between the socketed portion of the cap and the bore of a plug, and a drain passage in the wall of the body establishing communication 115 between the socket of the cap and the bore of the body below the plug.

In testimony whereof I affix my signature in presence of two witnesses.

CARL G. GUSTAFSON. [L.S.]
